DEEP WELL PUMP

Ethridge F. Ogles and J C. Ogles, Alvin, Tex., assignors to W. H. Hinton and Robert H. Hinton, both of Altus, Okla.

Application April 19, 1956, Serial No. 579,262

5 Claims. (Cl. 103—102)

This invention generally relates to a pump and more particularly relates to a deep well pump especially adapted for use in deep water wells for providing water flow for irrigation purposes and the pump may be employed wherever it is desired to pump liquid from a relatively deep well.

As is well known, well pumps have generally been classified as a shallow well type or a deep well type and the present invention relates to a deep well type which employs a step-by-step pumping operation including an improved type of pump construction for providing a relatively large volume of water with all elements of the pump being removable from the casing for replacement, repair, cleaning or the like.

Another object of the present invention is to provide a deep well pump employing a centrifugal type of impeller which is associated with spiral deflector blades and an auger type or inclined blade type impeller in spaced relation thereto for effectively converting the centrifugal force of the water to upward force of the water for pumping the water upwardly.

A further object of the present invention is to provide a deep well pump which may be provided with a number of pumping units as required for pumping the water from the well together with a centrifugal pump at the upper end of the well casing for providing water pressure for spraying the water in the event a spray type irrigation system is being employed.

Other objects of the present invention will reside in its simplicity of construction, ease of removing and replacing various elements, adaptations for its particular purposes and its relatively inexpensive manufacture and cost.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a side elevational view of the deep well pump of the present invention illustrated in position in a well casing which has been sectioned together with the pump casing which also is in section, in part, to illustrate the details and arrangements of the deep well pump;

Figure 2 is a longitudinal, vertical sectional view taken substantially upon a plane passing along section line 2—2 of Figure 1 illustrating the details of the pump at the upper end of the casing;

Figure 3 is a bottom plan sectional view taken substantially upon a plane passing along section line 3—3 of Figure 2 illustrating the details of the spiral blade-type auger at the entrance of the centrifugal pump at the upper end of the casing;

Figure 4 is a longitudinal, vertical sectional view taken substantially upon a plane passing along section line 4—4 of Figure 1 illustrating the details of construction of one of the pump units wherein the pump units are disposed

at predetermined levels for pumping water to a point above ground level;

Figure 5 is a transverse, plan sectional view taken substantially upon a plane passing along section line 5—5 of Figure 4 illustrating the relationship of the bearing spider to the intake opening of the bottom plate; and

Figure 6 is an exploded group perspective view illustrating the elements of one pumping unit.

Referring now specifically to the drawings, the numeral 10 generally designates the deep well pump of the present invention which is adapted to be inserted into well casings 12 disposed in the ground 14 for pumping water 16 from the bottom of the well to an accessible point above the ground level for use of the water. The casings 12 are generally standard in size and range generally from 8 to 12 inches in diameter. Inasmuch as the well casing 12 is usually provided with an irregular inner surface, the deep well pump 10 of the present invention includes an elongated tubular casing 18 which may be sectional with the sections joined together by the usual flange-type connection 20 wherein the casing 18 is disposed concentrically within the well casing 12 wherein the casing 18 may be supported therein in any suitable manner on the casing 12 wherein such support is not specifically illustrated in the drawings since it forms no part of the present invention. It is also pointed out that in some instances, the deep well pump 10 of the present invention may be inserted directly into the well casing without resorting to the casing 18 if the pump unit of the present invention is so constructed that it will fit the well casing 12.

Within the elongated casing 18 a plurality of pump units generally designated by the numeral 22 are disposed all of which are driven from a rotatable pump rod 24 which is sectional in construction and secured by connectors 26 which are internally threaded for engagement with the opposite externally threaded ends 27 of the pump rod sections 24.

Each of the pump units includes a bottom plate 28 having a concave upper surface 30 and an O-ring seal 32 disposed in a peripheral groove for engagement with the inner surface of the casing 18 thereby forming a seal in conjunction therewith. The center of the plate 28 is provided with an enlarged opening 34 and depending arms 36 are secured to the undersurface of the plate 28 with a central hub 38 being supported by the arms 36 wherein a bearing 40 is disposed in the central opening of the hub 38 for journaling the lower end of the pump rod 24 therein. The lower end of each of the arms 36 is cylindrical and designated by the numeral 42 for receiving a pin 44 which slides therein. A compression coil spring 46 is disposed between the inner end of each pin 44 and the bottom of the cylindrical portion 42 for urging the pins 44 outwardly into frictional engagement with the inner surface of the casing 18 thereby supporting the plate 28 within the casing 18 in concentric relation thereto. A thrust collar 48 is provided on the rod 24 below the hub 38 for assuring proper orientation of the hub and plate 28 on the pump rod 24.

Secured to the pump rod 24 immediately above the plate 28 is an impeller generally designated by the numeral 50 and including a central cylindrical hub portion 52 having a setscrew 54 for rigidly mounting the impeller on the rod 24 for rotation therewith. The cylindrical hub 52 extends from one end to the other of the impeller 50 and includes an upper cylindrical plate 56 and a lower plate 58 interconnected by a plurality of radial blades 60 which have substantially parallel inner and outer inwardly inclined edges 62 wherein the inner edges terminate at the edge of an opening 64 in the bottom plate 58 which is in alignment with the opening 34 in the bottom plate 28 for receiving water therefrom.

The area between the bottom end of the cylindrical hub 52 and the inner edges 62 of the blades 60 form substantially an annular conical shaped area for receiving water at the inner edges of the blades 64 by rotation of the impeller 50 causing outward and upward movement of the water due to the inclined relation of the bottom plate 58 and the inclined surface 66 on the bottom of the upper plate 56. It will be noted that the incline of the lower plate 58 forms substantially a convex lower end for the impeller which substantially rests against or adjacent to the concave surface 30 of the bottom plate 23 so that water will be pumped by centrifugal motion outwardly and upwardly of the impeller 50. It will be noted that the outer edges 62 of the blades 60 actually terminate in spaced relation to the inner surface of the casing 18 in order to permit upward passage of water from the impeller 50 past the upper circular plate 56.

A combination and deflector and bearing arrangement 68 is provided above the impeller 60 and includes a central hub portion 70 having an enlarged central socket 72 for receiving the hub 52 of the impeller 50 therein. At the lower end of the hub 70 is a circular plate 74 which is substantially equal in size to the upper plate 56 of the impeller 50 and plate 54 is disposed closely adjacent to the upper plate 56 without actually being in contact therewith. Depending from the periphery of the plate 74 is a plurality of spiral deflector blades 76 which taper to lower pointed ends 78. The outer periphery or edge of the blades 76 substantially define a cylinder and the inner edges of the blades 76 define a frusto-conical shape which is substantially the same shape as the outer periphery of the impeller 50 wherein the blades 76 will actually be disposed between the outer edges 62 of the blades 60 of the impeller 50 and the inner surface of the casing 18 substantially as illustrated in Figure 4 wherein water moving radially and upwardly from the blade 60 by the centrifugal force caused by the rotation of the water with the blade 60 will contact the upwardly inclined surface of the deflector blades 76 thereby giving an upward lift or upward movement of the water whereby a portion of the radial force of the water is converted to upward thrust for moving the water upwardly in the casing 18.

The hub 70 is provided with a central bearing 80 rotatably journaling the shaft 24 and the upper end of the hub 70 is provided with three radially extending arms 82 forming a support spider wherein the arms 82 are in the form of open-ended hollow sleeves slidably receiving a pin 84 provided with a compression coil spring 86 between the inner end of the pin 84 and the bottom of the tubular arm 82 thereby urging the pins 84 outwardly into engagement with the inner surface of the casing 18.

A collar 88 is disposed above the hub 70 and is secured on the rod 24 by a setscrew 90 for taking the thrust or weight of the rod 24 and transmitting it to the hub 70 and casing 18. If desired, a thrust bearing may be disposed between the thrust collar 88 and the upper end of the hub 70.

Disposed above the collar 88 in spaced relation thereto is an auger-type impeller generally designated by the numeral 92 which includes a central hub 94 secured on the shaft 24 by a setscrew 96 and a plurality of spiral blades 98 which coact to form a screw-type auger impeller. The blades 98 have the outer edges thereof conforming closely to the inner periphery of the casing 18 wherein added lift is given to the water being discharged from the deflector blades 78 thereby moving a relatively large volume of water upwardly within the casing.

As previously stated, a plurality of the pump units 22 may be employed with the pump units being disposed in spaced relation along the pump rod 24 wherein the rotatable elements include the impeller 50 and the impeller 92 with all of the other elements being stationary where-

by water is effectively moved upwardly in the casing at a relatively high volume rate.

The upper end of the casing 18 is provided with an extension 100 which may be of the same or less cross sectional area wherein the extension 100 is provided with a pump casing 102 having a centrifugal pump impeller 104 therein together with an auger type impeller 106 disposed in the extension 100 wherein the impeller 106 is similar in action to the impeller 92. The pump housing 102 is provided with a tangential discharge pipe 108 for connection to an irrigation line 110 wherein the pump impeller 104 together with the impeller 106 will effectively discharge water into the irrigation line at a considerable pressure for spraying the water from the irrigation line if deemed necessary.

The centrifugal impeller 104 may be of the conventional type and is provided with vertically elongated drive shaft 112 which has the upper end of the pump rod 24 secured thereto. The drive shaft 112 is supported in thrust bearings 114 by a thrust collar 116 disposed within support brackets 118. The stuffing box 120 is provided on the pump housing 102 and with suitable packing 122 being disposed therein together with a packing gland 124 which is adjusted by a bolt and nut arrangement 126. The support brackets 118 are connected to the thrust bearing assembly by bolts 128 which can be removed for removing the shaft 112 and the entire pump rod 24 with the various pump units 22 attached thereto. An electric motor 130 provided with a reduction gear 132 is supported on the brackets 118 in position for driving the shaft 112. It will be understood that any suitable power device may be employed for driving the shaft 112 and pump rod 24 wherein the speed should be relatively constant for producing a constant high volume flow of water from the casing 18.

What is claimed as new is as follows:

1. A deep well pump comprising an elongated tubular casing of constant cross sectional area, an elongated pump rod disposed in said casing, means for rotating said pump rod, bearing means rotatably supporting the rod in said casing, an impeller secured to said pump rod for rotation therewith, a bottom plate journaling said rod and disposed below said impeller in sealed relationship with the casing and being movable in relation thereto for removal, said bottom plate having a central opening for permitting passage of liquid, said impeller including spaced plates with substantially radial blades therebetween, the lower impeller plate having a central opening for receiving liquid from the opening in the bottom plate, the impeller blades and upper impeller plate terminating in spaced relation to the casing, the outer edges of said blades being inclined inwardly and upwardly, a plurality of spiral deflector blades disposed between the impeller blades and the casing for deflecting liquid upwardly, and an inclined blade type impeller mounted on said rod in spaced relation to the deflector blades for rotation therewith and for receiving liquid from the deflector blades and moving the same upwardly.

2. The combination of claim 1 wherein said bearing means includes a spider having a hub and radial arms with the hub rotatably journaling said pump rod, said arms having sockets in the outer ends thereof, pins slidably disposed in sockets, and spring means urging said pins outwardly into frictional engagement with the inner surface of the casing, a thrust collar on said rod in engagement with the upper end of the hub thereby supporting a portion of the pump rod.

3. The combination of claim 2 wherein said deflector blades are mounted on a plate equal in size to the upper impeller plate for guiding the axial flow of liquid.

4. The combination of claim 3 together with a centrifugal pump at the upper end of said casing including a centrifugal type impeller, a housing for said centrifugal impeller mounted on the upper end of the casing, and a spiral blade type auxiliary impeller at the entrance to

said housing for increasing the flow into the centrifugal type impeller, all of said impellers being driven by and rigid with said pump rod.

5. The combination of claim 4 wherein said bottom plate is provided with a peripheral gasket for sealing engagement with the casing, said bottom plate having a concave upper surface and said impeller being provided with a convex lower surface for positioning on said bottom plate.
